CLAIM

The ornamental design for a pet kennel, as shown and described.

DESCRIPTION

FIG. 1 is a perspective view of my new pet kennel;

FIG. 2 is a right side elevational view, the left side elevational view being a mirror image thereof of the pet kennel shown in FIG. 1;

FIG. 3 is a front elevational view of the pet kennel shown in FIG. 1;

FIG. 4 is a top plan view of the pet kennel shown in FIG. 1;

FIG. 5 is a rear elevational view of the pet kennel shown in FIG. 1;

FIG. 6 is a perspective view of an alternate embodiment of my new pet kennel;

FIG. 7 is a right side elevational view, the left side elevational view being a mirror image thereof of the pet kennel shown in FIG. 6;

FIG. 8 is a front elevational view of the pet kennel shown in FIG. 6;

FIG. 9 is a top plan view of the pet kennel shown in FIG. 6; and,

FIG. 10 is a rear elevational view of the pet kennel shown in FIG. 6.
